9 Claims. (Cl. 61—57)

1

This invention concerns the formation of concrete piles.

One object of the present invention is to permit of the formation of a pile having an increased or predetermined "set," i.e. resistance to displacement by application of weight thereto. A further object is to provide a pile which is expanded whilst in the ground so tightening the ground and thereby increasing the value of the skin friction and base loading properties of the pile. A further object is to consolidate a column of concrete whilst at the same time reducing the possibility of "waisting" at various points in the column which can occur when a pile is formed by any of the techniques now in common use. A further object is to provide a simplified method whereby a pile may be constructed without the permanent inclusion therein of metal reinforcement means and yet which is adapted to withstand great pressure. A further object is to provide a pile which is capable of withstanding a heavy loading using relatively light equipment. A further object is to improve the state of the art.

These and other objects are accomplished according to the present invention wherein a method of forming a concrete pile includes the steps of disposing a solid body permanently at or adjacent to the bottom of a bore, for a pile, or partially completed pile, charging the bore with concrete, withdrawing any drive tube or liner used when making the bore and consolidating and radially expanding the column of concrete introduced into the bore of the pile by means of a drive feed tube fitted with a preferably detachable compression member at its lower end, the axial alignment of the said drive feed tube and compression member within the bore of the pile being controlled by guide means permanently or temporarily located within the bore of the pile and positively engaging with the upper surface of the aforesaid solid body.

In one form of the invention wherein guide means for the drive feed tube are permanently disposed within the pile and serve as a reinforcement, a method of forming a reinforced concrete pile comprises making a bore with or without the aid of a lining or driving tube, locating a reticular and tubular, preferably a generally cylindrical, reinforcement within said bore upon a

2

hard standing, charging the bore with concrete, withdrawing any lining or driving tube employed and effecting consolidation and radial expansion of the concrete by tamping or vibrating a drive feed tube provided with a detachable shoe in a generally vertical direction within the reticular reinforcement, the drive feed tube being adapted to be withdrawn at one or more consolidation stages leaving a shoe permanently set within the pile after each withdrawal and being charged with concrete at the end of each consolidation stage but prior to withdrawal from the reticular reinforcement. Rupture of the concrete shell formed between the wall of the bore and the reticular reinforcement due to fluid seepage into an otherwise centrally located void is thereby obviated.

In a further embodiment of the invention, a method of constructing a concrete pile includes the step of consolidating and radially expanding the column of concrete introduced into the bore of the pile at any desired depth by means of a drive feed tube having a detachable compression member at its lower end when first introduced into the concrete column, the said drive feed tube being withdrawn a short distance, refilled completely with concrete, sealed and retamped on one or a succession of occasions as desired. The drive feed tube may conveniently be maintained in axial alignment with the bore of the pile by engagement with guide means either permanently or temporarily located within the bore of the pile. When filling the drive feed tube to obtain a local radial expansion at a selected point in the column it is preferred to use a relatively wet concrete so as to prevent the lower end of the drive feed tube becoming fouled with a hard cake of concrete. In this particular embodiment of the invention it will be appreciated that only one compression member or shoe is required for use with the drive feed tube. Each subsequent tamping operation is effected by means of the drive feed tube which is completely filled with concrete before each tamping operation and therefore acts as if it were a solid ram rod.

If a liner has been used when making the bore, this must be withdrawn prior to consolidating the concrete column by means of the drive feed tube and shoe. The drive feed tube consolidates the column of concrete by radial ex-

expansion from the centre of the column of concrete outwardly. The expanded concrete "keys" into the earth walls of the bore, passing through any reticular reinforcement present.

It will be appreciated that the number of shoes employed depends on the solidity of the several strata through which the bore passes. If the bore is made in firm ground, one consolidation stage only may be necessary, thus leaving one shoe only in the pile. If the bore is made through soft ground which "gives" under the outward expansion of the concrete, several consolidation stages may be required, necessitating leaving a plurality of shoes in the pile.

It is preferred to use a drive feed tube, the diameter of which is approximately the same as that of the shoe detachedly secured thereto. One method of achieving this result is by the provision of an inwardly directed annular flange disposed around the periphery of the shoe into which the drive feed tube engages. By such means, the area of contact between the tamping or vibrating means and the inside surface of the reticular reinforcement, if such be present, is relatively small and withdrawal of the drive feed pipe correspondingly facilitated.

Generally speaking, it is preferred to reduce the diameter of the drive feed pipe to a minimum commensurate with using a tube which does not bend or warp under the influence of tamping blows applied thereto whilst at the same time being of a sufficient diameter to allow free feed of the concrete.

It will be appreciated that the shape of the drive feed tube compression member or shoe is not critical. The impact surface may be for example, flat, hemispherical or conical. Within limits, the sharper the point of a conical impact surface, the less the power required to be delivered to the drive feed tube to ensure consolidation.

The permanently disposed solid body may be in the form of a conical shoe used for the initial drive. This shoe may have a spigot for engagement of a tube therewith near its outer periphery when a closed drive tube or liner is used for forming the bore of the pile. Both this shoe and the compression member engaging with the drive feed tube may be made from cast iron or may be fabricated from steel or may be a pre-cast reinforced concrete or any like substance sufficiently strong to withstand the pressure.

In order that it shall be possible to effect a positive temporary engagement between the permanently disposed solid body and the guide means for the drive feed tube temporarily located within the bore of the pile the upper surface of the permanently disposed solid body may be provided with one or more recesses. If a conical shoe is used the apex of the shoe forms a convenient means for locating the guide means. Alternatively, it may be found convenient to provide an annular recess on the inside surface of the said conical shoe by which guide means may be located.

The said guide means for the drive feed tube and compression member temporarily located within the pile may conveniently be in the form of a metal rod or tube located centrally within the bore of the pile, the compression member being drilled centrally so as to be capable of sliding axially upon the said guide rod or tube. A guide rod or tube is preferably disposed within the drive feed tube but it will be appreciated that guide means may also be provided for the

drive feed tube and compression member disposed outside the drive feed tube, i. e. between the latter and the walls of the bore. For example, two or more guide rods may be located in an annular recess in a conical shoe constituting the permanently disposed solid body and the compression member may be provided with two or more complementary rebated surfaces adapted to align themselves with the two or more guide rods.

When employing guide means for the drive feed tube and compression member which are located but temporarily within the bore of the pile it is found convenient to provide ancillary guide means for the drive feed tube in the shape of a bracket which is detachably secured to the top end of a guide rod or tube. The diameter of this said bracket is but slightly less than the internal diameter of the drive feed tube and serves to prevent any wobbling of the drive feed tube as it slides up and down the guide rod.

When employing a centrally disposed guide rod or tube the compression member consists of a conical shoe having a central drilling therein adapted to slide upon the said guide rod or tube. It is preferred to use a compression member of a smaller diameter than the diameter of the bore of the pile because by so doing a film of concrete is disposed between the wall of the bore and the drive feed tube and this ensures that the drive feed tube is in a relatively clean condition when it is withdrawn from the bore at the end of each tamping operation.

When first charging the bore of the pile after the initial drive, and when first charging the drive feed tube before withdrawal after each tamping operation except the last, it is preferred to use a small quantity of dry concrete because this reduces the possibility of back pressure and increases driving resistance at the toe of the pile.

The invention as applied to the formation of a reinforced concrete pile will now be more particularly described by reference to the accompanying drawings in which—

Figures 1 to 8 are vertical medial sections showing successive stages in the formation of a reinforced concrete pile.

A bore is formed in the usual way either by driving a tube 11 having a detachable shoe (not shown) or by boring with the use of tube 11. A charge 12 of stiff plastic concrete is then introduced into the lower end portion of the bore. A spiral reinforcement 13 having its lower end fixed to a disc shaped metallic anchor plate 14 is then inserted. The anchor plate 14 need not necessarily be attached to the lower end portion of the reinforcement. No anchor plate is required at all if a hard standing can be provided for the reinforcement either by a driving shoe previously used in conjunction with tube 11 and left at the bottom of the bore or if a rock stratum has been encountered.

The bore is then filled up with stiff plastic concrete 15 (Figure 4) and tube 11 is withdrawn. A shoe 16 of external maximum diameter slightly less than that of the interior of the reinforcement is then placed inside the reinforcement on top of the concrete and a drive feed tube 17 of less diameter than that of the interior of the reinforcement is placed on the shoe and driven down through the plastic concrete column either by use of a drop hammer or vibratory hammer (not shown). Tamping or vibrating is continued with consolidation and compressing of the concrete until the position is attained where-

in shoe 16 abuts against the anchor plate 14 (Figure 5) or a suitable set is obtained.

The reinforcement acts as a guide for the drive feed tube and for the shoe whilst the reinforcement is itself centralised in relation to the concrete column.

During the downward movement of the shoe and drive feed tube the concrete is expanded through the reinforcement substantially equally in all directions. The drive feed tube is then filled with a concrete charge 18 (Figure 6), tube 17 is then withdrawn, a new shoe 19 put on top of the pile and the operation of driving is repeated as many times as may be found necessary.

On the final filling of the drive feed tube a relatively wet charge 20 of concrete is preferably used. This relatively wet concrete is advantageous in easily filling up the void created by the drive feed tube after the drive feed tube has been withdrawn for the last time but it has been found that more efficient driving and consolidating effect obtains if stiffer or dryer concrete charges are utilised in the earlier stages. It has been found that by use of the invention some of the gravel or other aggregate in the concrete is driven to the outside periphery of the pile thereby providing a coarse adhesive surface readily adapted to "key" against the earth wall.

Whilst it is preferred to employ a tubular reinforcement which is of generally cylindrical shape, a reinforcement of polygonal such as square shape may be used. The reinforcement may be wholly of helical form that is to say without incorporating any directly vertically extending members.

A reinforced concrete pile including a plurality of shoes or solid bodies of a cross section commensurate with the diameter of the reticular reinforcement is novel and is included within the scope of the invention.

The invention as particularly applied to the formation of a concrete pile having no permanent inclusion therein of metal reinforcement means will now be more particularly described by reference to the accompanying drawings in which:

Figures 9 to 16 are vertical medial sections showing successive stages in the formation of a concrete pile.

Figure 17 is a vertical medial section showing an alternative form of guide means, and

Figure 18 is a cross-section on the line XVIII—XVIII of Figure 17.

A bore 21 is formed by driving a tube 22 fitted with a detachable conical shoe 23 at its bottom end. A guide rod 24 of any suitable section is then placed inside the tube and is centralized on the conical shoe at the bottom of the pile; concrete is then introduced into the drive tube after which the drive tube is withdrawn (Figure 12). A second conical shoe 26, preferably of smaller diameter than the permanently disposed conical shoe at the bottom of the pile and having a hole 27 drilled centrally through it is then placed over the guide tube 24, a bracket 28 forming a top guide of slightly smaller diameter than a drive feed tube fitted to the top of the guide tube and a drive feed tube is then placed over this bracket and brought to rest on the second shoe. The drive feed tube and shoe is then driven down to its desired depth thereby consolidating and radially expanding the existing concrete column (Figure 14). The drive feed tube is filled with concrete 29 and then

withdrawn leaving the second shoe in the concrete column. This tamping operation is repeated as often as desired in order to consolidate the column of concrete (Figure 15). At the end of the operations the guide rod is withdrawn (Figure 16) preferably before the last charge of concrete is introduced into the drive feed tube.

As shown in Figures 17 and 18 the permanently disposed solid member at the base of the pile is provided with an annular groove 30 and vertical rods 31 engage in said annular groove and lie parallel to but on the outside of the drive feed tube. The rods 31 serve as guide means for the conical shoe 33 which is provided with a pair of lugs 34 making a sliding engagement with the said rods.

Figures 19-22 are vertical medial sections of another embodiment of the invention.

A bore 35 having a solid body 36 permanently disposed at the bottom thereof is charged with concrete 37 and the driving tube or liner then withdrawn (not shown). A drive feed tube 38, having a detachable compression member 39 at its lower end and a sealing cap 40 at its upper end is then introduced into the column of concrete (Figure 19), and tamped so as to consolidate and radially expand the column of concrete (Figure 20). The drive feed tube is then withdrawn a short distance leaving the compression member or conical shoe 36 permanently disposed in the pile. The act of withdrawal leaves a void 41 at the top of the drive feed tube (Figure 21). The cap 40 is removed, the drive feed tube completely refilled, the cap replaced and the drive feed tube again tamped. This procedure is repeated as often as desired until a localised expansion 42 of the concrete column at a predetermined depth is effected (Figure 22).

It will thus be seen that by means of the present invention a method of forming a concrete pile is provided in which relatively light ancillary equipment is employed. By consolidating a column of concrete in the bore of a pile without the presence of any drive tube or liner and using a drive feed tube maintained in axial alignment within the said bore, the concrete is urged outwardly from the centre of the bore and is thus subjected to radial expansion. A pile of relatively uniform cross section may be produced or, if tamping operations are repeatedly carried out at a predetermined depth, a localised expansion may be effected. It will further be appreciated that the invention provides a method of forming a concrete pile requiring if desired, a minimum quantity only of reinforcement material permanently disposed therein.

I declare that what I claim is:

1. A method of forming a concrete pile which comprises, in combination, the steps of disposing a solid body permanently at the bottom of a bore for a pile, disposing guide means in the bore of the pile positively engaging with the solid body, charging the bore with concrete, withdrawing completely any drive tube used when making the bore so as to leave the concrete in intimate contact with the walls of the bore throughout the length of the said bore, and then consolidating and radially expanding the column of concrete throughout its length by means of a drive feed tube fitted with a detachable compression member at its lower end, using the guide means for maintaining axial alignment of the said drive feed tube and compression member within the bore of the pile during tamping.

2. A method of forming a concrete pile comprising, in combination the steps of disposing a solid body permanently at the bottom of a bore for a pile, temporarily disposing guide means within the bore of the pile positively engaging with the solid body, charging the bore with concrete, withdrawing completely any drive tube used when making the bore so as to leave the concrete in intimate contact with the walls of the bore throughout the length of the said bore, and then consolidating and radially expanding the column of concrete throughout its length by means of a drive feed tube fitted with a compression member at its lower end, using the guide means to maintain axial alignment of the said drive feed tube and compression member within the bore of the pile and finally withdrawing the guide means from the consolidated concrete column.

3. A method of forming a reinforced concrete pile which comprises, in combination, the steps of disposing a solid body permanently at the bottom of a bore for a pile, permanently disposing a reticular and tubular reinforcement within the bore, charging the bore with concrete, withdrawing completely any drive tube present from making the bore so as to leave the concrete in intimate contact with the walls of the bore throughout the length of the said bore, and then consolidating and radially expanding the column of concrete throughout its length by tamping a drive feed tube fitted with a detachable compression member at its lower end within the column of concrete, utilising the reticular and tubular reinforcement to maintain axial alignment of the drive feed tube during each tamping operation.

4. A method of forming a concrete pile comprising, in combination, the steps of disposing at the bottom of a bore for a pile a conical shoe having an upwardly directed spigot adapted to engage with the drive tube used to make the bore initially, introducing guide means for a drive feed tube and compression member into the bore so as to positively engage with the upper surface of the conical shoe, charging the bore with concrete, withdrawing completely the drive tube so as to leave the concrete in intimate contact with the walls of the bore throughout the length of the said bore, and then consolidating and radially expanding the column of concrete throughout its length by tamping a drive feed tube fitted with a detachable compression member at its lower end within the column of concrete, the guide means serving to maintain axial alignment of the said drive feed tube and compression member within the bore of the pile during each tamping operation.

5. A method of forming a concrete pile comprising, in combination, the steps of disposing a solid body having at least one recess in its upper surface permanently at the bottom of a bore for a pile, temporarily introducing into the bore at least one vertically disposed metal member adapted to engage within the said recess, charging the bore with concrete, withdrawing completely any drive tube used for making the bore so as to leave the concrete in intimate contact with the walls of the bore throughout the length of the said bore, and then consolidating and radially expanding the column of concrete by means of a drive feed tube fitted with a detachable compression member at its lower end, using the vertically disposed metal member to maintain axial alignment of the drive feed tube during each tamping operation.

6. A method of forming a concrete pile comprising, in combination, the steps of disposing an inverted conical shoe permanently at the bottom of a bore for a pile, introducing a metal rod centrally into the bore of the pile and positively engaging said rod within the apex of the inverted conical shoe, charging the bore with concrete, withdrawing completely any drive tube used when making the bore so as to leave the concrete in intimate contact with the walls of the bore throughout the length of the said bore, and consolidating and radially expanding the column of concrete throughout its length by tamping a drive feed tube fitted with a detachable compression member at its lower end having a central passage therethrough adapted to slidably engage with the metal rod during each tamping operation.

7. A method of forming a concrete pile comprising, in combination, the steps of disposing an inverted conical shoe permanently at the bottom of a bore for a pile, locating a metal tube centrally within the bore of the pile so as to engage within the apex of the inverted conical shoe, charging the bore with concrete, withdrawing completely any drive tube used when making the bore so as to leave the concrete in intimate contact with the walls of the bore throughout the length of the said bore, disposing a drive feed tube fitted with a centrally drilled inverted conical shoe at its lower end in sliding engagement with the metal tube, temporarily securing a bracket to the top end of the metal tube within the drive feed tube and consolidating and radially expanding the column of concrete throughout its length by the application of an axial vibratory movement to the drive feed tube.

8. A method of forming a reinforced concrete pile comprising, in combination, the steps of making a bore for a pile with a drive tube fitted with an inverted conical shoe at its lower end, locating a reticular and tubular reinforcement within said bore so as to positively engage with the said inverted conical shoe, charging the bore with concrete, withdrawing completely the drive tube leaving the inverted conical shoe permanently disposed at the bottom of the bore so as to leave the concrete in intimate contact with the walls of the bore throughout the length of the said bore, consolidating and radially expanding the column of concrete throughout its length by tamping a drive feed tube provided with a detachable inverted conical shoe at its lower end in a generally vertical direction within and guided by the reticular reinforcement, withdrawing the driven drive feed tube after first recharging it with concrete so as to fill up the void, leaving the inverted conical shoe permanently disposed within the bore of the pile, refitting the drive feed tube with a fresh inverted conical shoe and repeating the tamping operation a plurality of times.

9. A method of forming a concrete pile comprising, in combination, the steps of disposing a solid body permanently at the bottom of a bore for a pile, disposing guide means for a drive feed tube within the bore of the pile positively engaging with the solid body, charging the bore with concrete, withdrawing completely any drive tube used when making the bore, consolidating and radially expanding the column of concrete by tamping a drive feed tube within the column of concrete having a detachable compression member at its lower end when first introduced into the concrete column, withdrawing the drive feed tube a short distance, filling the void created at the top of the drive feed tube with fresh concrete,

9

sealing the top of the drive feed tube, and repeating the tamping operation successively so as to produce a localised expansion of the column of concrete at a predetermined depth, whilst utilising the guide means to maintain axial alignment of the drive feed tube during each tamping operation.
